(57) CLAIM

The ornamental design for barbecue grill brush, as shown and described.

DESCRIPTION

FIG. 1 is a front elevational view of a barbecue grill brush; FIG. 2 is a left side elevational view thereof; FIG. 3 is a right side elevational view thereof; FIG. 4 is a top plan view thereof; FIG. 5 is a bottom plan view thereof; and, FIG. 6 is a rear view thereof.
The broken lines are for the purposes of illustrating portions of the barbecue grill brush and form no part of the claimed design.
